UNITED STATES PATENT OFFICE.

JEFFERSON D. TRAMMELL, OF FORT WORTH, TEXAS.

PIPE OF CONCRETE AND THE LIKE.

1,344,779.

Specification of Letters Patent. Patented June 29, 1920.

Application filed November 18, 1918. Serial No. 263,029.

To all whom it may concern:

Be it known that I, JEFFERSON D. TRAMMELL, a citizen of the United States, and resident of Fort Worth, in the county of Tarrant and State of Texas, have invented certain new and useful Improvements in Pipes of Concrete and the like, of which the following is a specification, reference being had therein to the accompanying drawing.

10 Concrete pipes are used for various purposes including the conveying of water, but the difficulties resulting from expansion and contraction are great and far more serious than when metal pipes are employed. Generally speaking, metal pipes expand and contract through changes in temperature only, while concrete pipes, which have approximately the same coefficient of expansion, expand and contract as much, or even 15 more, through variation in moisture, so that they may expand and contract, under both temperature and moisture changes, twice as much as metal would under the same conditions. Further, concrete is not so strong 20 as metal nor so well suited to withstand the effects of expansion and contraction.

With ordinary concrete pipes, a rigid joint results in fracture and leakage, very often, and besides, if slip joints are made 25 they are quickly worn because of the coarse texture, softness and brittleness of the material.

So far as applicant is aware, there has never been a fully successful way of joining concrete pipe sections, and for this reason the use of this otherwise highly desirable material has been limited.

The methods of joining cast iron water and gas pipes have reached a high degree of 30 perfection, but these methods do not appear to be applicable to concrete pipes of ordinary character, and for reasons above suggested.

My invention provides a slip joint in concrete pipes of the bell and spigot type commonly employed in cast metal pipes, and at the same time eliminates practically all injurious wear of the slipping surfaces, thus making available a method resembling that 35 which has proved so satisfactory in metal pipes. The result is obtained by facing either the spigot or the interior of the bell, or both, with smooth metal, and thus the common methods of joining metal pipes by 40 calking or otherwise become available, the concrete pipes being provided with rein-

forcement adapted to resist the strains due to calking as well as other strains commonly met. The facing may be of any suitable material but is preferably of metal which 45 is not readily corrodible, copper being suitable.

In the accompanying drawings, Figure 1 is a side elevation, partly in axial section, showing connected pipes.

Fig. 2 is an enlarged, partial, axial section showing preferred forms used at the pipe joints.

Fig. 3 is a cross section through the joint.

In these figures, A represents the body of 50 a pipe section, B its bell and C its opposite end portion or spigot. The interior of the bell is provided with a lining band D, the face of which, at least, is preferably not readily corroded, and which is provided 55 with outwardly projecting flanges E which extend into the concrete molded about the ring and thus prevent relative longitudinal movement of the pipe and ring. At some distance outside the ring or band annular 60 reinforcing members F are embedded in the concrete and still farther from the axis additional concentric reinforcing members F' are embedded in like manner when desired, these members varying in number and size 65 with the particular conditions existing, *e.g.*, increasing with the diameter of the pipe and the pressure to be sustained. Longitudinal reinforcing bars G extend substantially from end to end of the pipe section, 70 curving outwardly into the walls of the bell, returned by a curve G' near the end of the bell and extending back to some distance in the bell wall, parallel to their original direction. The walls of the telescoping ends 75 of the sections contain, if desired, lighter fabric-like metal reinforcing units, H, which, like the members F, F', may have their ends or marginal portions overlapped, with or without connection other than the 80 concrete in which they lie.

The spigot end portion I of each pipe is of greater diameter at one point than the body portion, the pipe sloping away on each side from the annular enlargement thus 85 formed which nearly fits the interior of the bell of the next section. A little farther from the end of the spigot the latter is provided with an annular depression J to receive and hold against longitudinal slipping 90 oakum K or the like, and still farther from the end is a second annular depression J'

to receive in like manner other calking material, such as cement or lead L. The enlargement prevents the fibrous material from advancing too far when pressed by the lead 5 which is compacted in the usual way with a calking implement, and both depressions, as has been suggested, prevent undesirable movement of the material along the spigot. The strong radial force exerted by the calking 10 material is safely resisted by the reinforcing metal. Preferably the spigot portion, especially when the walls are thin, is reinforced by bars F², similar to the bars F, F', which resist strains of compression. 15 The metal lining band does not unite with the calking material but allows the latter to slip under the great strains due to variation in temperature and moisture, already mentioned, and no leakage is usually caused 20 by such adjustment no matter how often the slight movements may occur.

Preferably, the spigot is provided with a thin coating M of asphaltum to facilitate the safe adjusting movements and to lessen 25 the chance of injury by the calking tool.

Obviously the facing metal might be on the spigot and the grooves or depression might be in the bell, or both bell and spigot might have depressions. This latter construction is however less desirable, and 30 facing the spigot makes it desirable to cover the facing metal to protect it from injury by rough handling before the sections are joined.

35 It is also evident from the drawing that the lead is a relatively narrow ring on the spigot and that the end portions of the bell and spigot are spaced apart radially so that slight movement, in any direction, from 40 alinement causes a rocking on the ring without material effect thereon or any dangerous

strain upon the concrete, oakum offering no material resistance to deflection. Attention may be called to the fact that the spigot can be completely withdrawn from the bell 45 and replaced without breaking or deforming any part,—a feature especially useful in repairing.

What I claim is:—

1. A concrete pipe joint comprising a bell 50 member having a longitudinally extending portion of its interior provided with a cylindrical hard metal, or other smooth, lining not exceeding in diameter at any point the diameter of any part nearer the bell's end, 55 a spigot lying in the bell, and a narrow ring of calking material compacted between said lining and spigot.

2. A concrete pipe joint comprising a bell member having a longitudinally extending portion of its interior provided with a cylindrical metal or other smooth lining not exceeding in diameter the diameter of any part of the bell lying nearer the bell's end, a 60 spigot lying in the bell and having a circumferential groove, and a narrow ring of calking material compacted into said groove 65 and extending outwardly against said lining.

3. In a concrete pipe joint, a cylindrical bell member having a longitudinal portion of its interior cylindrical and lined with metal or other material giving a smooth surface, a smaller spigot member lying in the bell and having an annular external depression, and an annular body of calking 70 material compacted between the overlapping surfaces, in anchored engagement with the spigot, and resting outwardly against the lined portion of the bell.

In testimony whereof I hereunto affix my 80 signature.

JEFFERSON D. TRAMMELL.
